UNITED STATES PATENT OFFICE.

ROBERT DUNLAP, OF NEW YORK, N. Y.

DESIGN FOR A HAT-LINING.

SPECIFICATION forming part of Design No. 13,371, dated October 31, 1882.

Application filed September 29, 1882. Term of patent 7 years.

To all whom it may concern:

Be it known that I, ROBERT DUNLAP, a citizen of the United States, residing at New York, in the county and State of New York, have invented and produced a new and original Design for Hat-Linings, of which the following is a specification, reference being had to the accompanying drawings.

The novel feature of this design consists of a plain band extending lengthwise to the lining, in the center thereof, and of radial corrugations on opposite sides of the band, whereby a characteristic appearance is given to the lining.

In the accompanying drawings, Figure 1 represents a sectional inverted plan view, and Fig. 2 a vertical cross-section.

Similar letters indicate corresponding parts. The letter A designates the plain band, which extends lengthwise to the lining, in the center thereof—namely, the entire length of the lin-

ing; and B indicates the radial corrugations on opposite sides of the band, the point from which these corrugations radiate being the center of the lining.

With a view to increase the effect of my design the band A may be provided with a label of any usual or suitable character.

What I claim as new, and desire to secure by Letters Patent, is—

The design for a hat-lining, consisting of a plain band extending lengthwise to the lining, in the center thereof, and of radial corrugations on opposite sides of the band, as shown and described.

In testimony whereof I have hereunto set my hand and seal in the presence of two subscribing witnesses.

ROBT. DUNLAP. [L. S.]
